CLOCK

Max E. Schlenker, Peru, Ill., assignor to General
Time Corporation, New York, N. Y., a corpora-
tion of Delaware

Application May 17, 1951, Serial No. 15,223

Term of patent 14 years

(Cl. D42—7)

To all whom it may concern:

Be it known that I, Max E. Schlenker, a citizen of the United States, residing at Peru, in the county of La Salle and State of Illinois, have invented a new, original, and ornamental Design for a Clock, of which the following is a specification, reference being had to the accompanying drawing, forming a part thereof.

The single figure is a perspective view of a clock, embodying my new design.

The essential features of my design for a clock reside in the fact that it is symmetrical on all sides, each side having the same identical curves with those of the other three sides.

I claim:

The ornamental design for a clock, substan-
tially as shown and described.

MAX E. SCHLENKER.
